SEWARD W. MANN, OF PITTSBURGH, PENNSYLVANIA, ASSIGNOR TO H. KLEINHANS COMPANY, OF PITTSBURGH, PENNSYLVANIA, A CORPORATION OF PENNSYLVANIA.

APPARATUS FOR CONTROLLING THE FLOW OF CURRENT FROM DIRECT-CURRENT GENERATORS.

Application filed November 24, 1925. Serial No. 71,154.

My invention relates to means for controlling the flow of current from direct current generators, and is particularly adapted to circuits in which the resistance of the consuming element varies widely at each operation, as in arc-welding.

In general, this invention has the same objects as that shown and described in my application, Serial Number 735,310, filed 10 September 2, 1924; but, more particularly, its main object is to provide the system containing the principles of that application with a switching means whereby the system can be set for the consumption of certain 15 amounts of current and the amperage for any setting will remain substantially constant irrespective of variations of resistance in the current-consuming means. This and further objects will be explained herein- 20 after in detail.

The accompanying drawing shows the generator system diagrammatically, the switching means being shown partly dia- 25 grammatically and partly in plan view.

On the drawing, 1 designates the armature of a direct current generator, having two leads 2 and 3 with their outer ends connected to some translating or current-consuming device, such as the arc welding terminals 4 and 5. The lead 2 preferably includes as a part thereof a reactance coil 10, while the lead 3 has interposed therein more or less of a resistance 9 and a switching means presently to be described. The latter lead connects one brush of the armature 1 to one terminal of the resistance 9, and the wire 8 is connected at one end to the welding electrode 5 and at the other end to the movable switch arm 12.

The resistance 9 contains three sections 13, 14 and 15, but may contain more or less. The section 13 comprises the two parallel conductors or bus-bars 16 and 17 between which are three resistance wires 18. The section 14 comprises two parallel conductors or bus-bars, one being marked 19 and the other being an extension of the bus-bar 17. Two resistance wires 20 are connected to the bus-bars 17 and 19. The section 15 comprises two parallel conductors or bus-bars one being marked 21 and the other being a prolongation of the bus-bar 19. A resistance wire 22 is connected to the bus-bars 19 and 21. The particular resistance shown

illustrates only one of many kinds of resis- 55 tances which might be employed. The number of resistance wires bridging the bus-bars of the individual sections will vary in accordance with the demands of the work to be done. The wire 3 is shown connected 60 to the bus-bar 16.

I provide the movable switch blade or member 12 which is pivoted to swing in two planes at right angles to each other. 22' is a shaft or pivot carrying the block 23 in 65 which one end of the switch member 12 is pivoted by means of the pin 24 extending through the block 23 and the member 12, the pin 24 being at right angles to the pivot 22. The blade of the switch is adapted to 70 engage any one of the pairs of contacts 25, 26, 27 and 28. The lead 3 is electrically connected to the contact 25 through the wire 29. The wire 30 connects the bus-bar 17 to the contact 26; the wire 31 connects the bus- 75 bar 19 to the contact 27; and the wire 32 connects the bus-bar 21 and the contact 28.

The switch member 12 carries a blade or contact 33 insulated therefrom. This blade engages the contact 34 when the switch 80 member 12 engages the contact 25; the contact 35 when the member 12 engages the contact 26; the contact 36 when the member 12 engages the contact 27; and the contact 37 when the member 12 engages the contact 85 28. The contact 34 is adjustably connected by the wire 43 to a point, as 38, in one of the wires 18. The contact 35 is connected adjustably by the wire 44 to a point, as 39, in another one of the wires 18. The contact 90 36 is adjustably connected by the wire 45 to a point, as 40, in one of the wires 20. The contact 37 is adjustably connected by the wire 46 to a point, as 41, in the wire 22. A wire 42 connects the blade 33 to one ter- 95 minal of the field winding 6, and the wire 11 connects the other terminal to a selected point, as 7, on the lead 2, or to a point on the reactance 10.

If the switch member 12 is moved to 100 position α , in which it engages the contact 25, and the contact 33 engages the contact 34, current will flow from the armature 1 through the lead 3, the wire 29, the contact 25, the member 12, the lead 8, the welding electrode 5, the work 4, the lead 2 and the reactance 10 to the armature 1. At the same time, the field current flows from the

armature through the lead 3, a portion of one wire 18, the wire 43, the contact 34, the blade 33, the wire 42, the field winding 6, the wire 11, the lead 2, and the reactance 10 5 back to the armature 1.

Let it be assumed that 300 amperes will flow in the load circuit during a welding operation. The points of connection of the field circuit to the load circuit and the 10 amount of resistance in the field circuit are so chosen that no matter whether the welding electrodes are directly in contact with each other or an arc of any size is drawn between them, a current of 300 amperes 15 flows in the load circuit. This uniformity of current flow is due to the fact that the field is strengthened or weakened in proportion to the voltage drop across the welding electrodes caused by changes in resist- 20 ance between the electrodes.

If it is desired to weld with a current of lower amperage, as 200 amperes, the switch member is moved to position *b* in which all the resistance wires 18 of the section 13 are 25 inserted in the load circuit, and at the same time a larger resistance has been introduced into the field circuit by the wire 44 connected at the point 39 on one of the resistance wires 18. The point 39 of connection of the wire 30 is selected so that the field will be strengthened or weakened proportionately with the voltage drop between the welding electrodes. When the points of 30 connection of the field circuit have been 35 properly selected, the current between the electrodes will be 200 amperes when the arc is struck, and whatever the size of the arc.

If it is desired to weld with 100 amperes, the switch member is moved to position *c* 40 in which all the section 13 and a part of the section 14 are inserted in the field circuit, and all of the sections 13 and 14 are inserted in the load circuit. The amount of resistance between the armature and the 45 points of connection of the field circuit to the load circuit, and the amount of resistance in the field circuit are so selected and proportioned that variations in voltage drop between the electrodes is impressed on the field in the proper amounts to cause a constant flow of 100 amperes in the load circuit.

If a welding current of 30 amperes is desired, the switch member 12 is moved to position *d* 50 in which all of the resistance sections are placed in the load circuit, and the sections 13 and 14 and a part of the section 15 are placed in the field circuit. This resistance being properly chosen, the current flowing through the electrodes will be held at 30 amperes whatever the resistance may be between the electrodes.

By employing the several resistance sections the welding can be done at lower values of current more easily, due to the reserve

voltage stored up or being dissipated in the resistance, the result being that the arc could be lengthened to a greater extent without its extinction. Assuming that there is a 6 volt drop from position *a* to position *b*, 70 six volts more have been given to the flexibility of the arc. To compensate for this six volts added resistance, the generator, automatically, due to the change in its field connection generates an additional six volts 75 which is dissipated in the resistance.

By moving the switch member 12 to position *c*, still more resistance, for example, a drop of four more volts, is introduced, which gives a ten volt drop or reserve voltage to 80 assist the flexibility of the arc.

By moving the switch member 12 to position *d* another section of resistance, giving an additional drop of two volts, is introduced, which gives a total voltage drop of 85 twelve volts, which makes the welding at exceptionally low current values very easy.

The making of the welding easier at the different lower values of current is due to the introduction of additional resistance into the circuits, which causes the generator to 90 operate at a higher voltage.

I claim—

1. In an apparatus for regulating the flow of current from a direct current generator through a translating device subject to widely varying current consumption, a shunt field winding for the generator, resistance for the load and field circuits, a switch for closing both circuits in a plurality of selective settings to vary said resistances, and connections whereby when the said circuits are closed by the said switch, resistance in the said circuits is so proportioned that, at any setting of the switch, field strength 105 will be such as to cause a substantially constant current to flow in the load circuit irrespective of variations in the resistance of said translating device.

2. In an apparatus for regulating the flow 110 of current from a direct current generator through a translating device subject to widely varying current consumption, a shunt field winding for the generator, resistance for the load and field circuits, switching means 115 for closing each of the circuits in a plurality of selective settings to vary said resistances, and connections whereby when the said circuits are closed by the said switching means, resistance in the said circuits is so proportioned that, at any setting of the switching means, field strength will be such as to cause a substantially constant current to flow in the load circuit irrespective of variations in the resistance of said translating device.

3. In an apparatus for regulating the flow 120 of current from a direct current generator through a translating device subject to widely varying current consumption, a shunt field winding for the generator, resistance 125

- for the load and field circuits, switching means to selectively set the resistance in the load circuit to give any one of a number of predetermined working load currents, 5 switching means for correspondingly selectively setting the field resistance in such predetermined amount with relation to the load circuit resistance in any setting thereof as to cause a substantially constant current to flow in the load circuit irrespective of 10 variations in the resistance of said translating device.

Signed at Pittsburgh, Pa., this 12th day of November, 1925.

SEWARD W. MANN.
